(57) **CLAIM**

We claim the ornamental design for a thread cutter, as shown and described.

DESCRIPTION

FIG. 1 is a perspective view showing a thread cutter according to our design;

FIG. 2 is a front view of the same;

FIG. 3 is a rear view of the same;

FIG. 4 is a top plan view of the same; and,

FIG. 5 is a right side view of the same, a left side view being symmetrical to the right side view.

The broken lines shown in the drawings illustrate portions of the thread cutter that form no part of claimed design.
